(57) CLAIM

The ornamental design for a hydrating lounge chair, as shown and described.

DESCRIPTION

FIG. 1 is a top and front isometric view of a hydrating lounge chair, showing my design;

FIG. 2 is a rear oblique view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken line showing of portions of the hydrating lounge chair is for illustrative purposes only and forms no part of the claimed design.
